(57) **CLAIM**

The ornamental design for a display screen or portion thereof with animated graphical user interface, as shown and described.

DESCRIPTION

FIG. 1 is a front view of a display screen or portion thereof with animated graphical user interface, showing a first image of my new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the animated graphical user interface transitions sequentially between the images shown in FIGS. 1-6. The process or period in which one image transitions to another forms no part of the claimed design.

The outermost broken lines shown in the figures illustrate a display screen or portion thereof, and form no part of the claimed design.
